US0D1078278S

(12) **United States Design Patent** (10) **Patent No.:** **US D1,078,278 S**
(45) **Date of Patent:** **** Jun. 10, 2025**

(54) **ORGANIZER**

(71) Applicant: **Spectrum Diversified Designs, LLC**,
Streetsboro, OH (US)

(72) Inventor: **Bridget Hunt**, Cleveland, OH (US)

(73) Assignee: **Hologram Holdings I, Inc.**, San
Clemente, CA (US)

(**) Term: **15 Years**

(21) Appl. No.: **29/869,141**

(22) Filed: **Dec. 22, 2022**

(51) **LOC (15) Cl.** **07-01**

(52) **U.S. Cl.**

USPC **D7/501**
